**DEVICE FOR USE IN SECURING PANELS TO
WALL AND CEILING STRUCTURE IN ROOMS**

Dennis E. Cleary, Ukiah, Calif.

Application July 11, 1955, Serial No. 521,048

3 Claims. (Cl. 189—34)

This invention relates to a device or nailing strip for securing panels, such as plasterboard and the like, to wall and ceiling structure in rooms so as to provide side walls, or a ceiling, or both for a room with space behind the panels for air or for fibrous or other insulating material.

One of the objects is the provision of simple, economical and easily used means for supporting wall panels, such as plasterboard and the like, spaced from a masonry wall of concrete, or blocks of concrete or the like, brick, or other material.

A still further object of the invention is the provision of simple, economical and easily used means that is non-moisture absorbent, and that is not subject to deterioration from moisture, nor warpage, etc., for supporting wall panels coplanar on room wall structure spaced from such structure, and which means provides for nailing such wall panels thereto.

One of the problems in buildings having outer walls of masonry is to secure wall panels, such as plasterboard, to said walls in spaced relation thereto so as to provide a space between the masonry walls for heat insulation, whether merely air or one of the many insulation materials. Plasterboard, which includes panels of gypsum and any of the preformed panels, plywood, etc., are normally nailed in position. The provision of wooden strips or studding is not satisfactory, because, among other objections, they are moisture absorbent and are subject to deterioration, warpage, insect infestation, etc., and are expensive and difficult to secure to masonry, flammable and occupy an excessive amount of space.

The outer walls of masonry provide adequate strength for supporting the inside wall panels, hence, there is no need to provide means for securing the panels in position that must also provide structural strength for the building walls. The panels themselves are self supporting, but must be held in position, and one object of the present invention is to provide the means for so holding the panels in said position by nailing said panels to said means in the same manner as though the panels were nailed to wood, but which means is free from the objections to the use of wood and may readily be secured to the masonry walls.

Also, in suspended ceilings, or ceilings suspended below ceiling joists or beams, difficulty has heretofore been had in making such a suspended ceiling of plasterboard or panels. Here again, wood is not suitable, being awkward to handle, heavy, subject to warpage under changes in temperature and heat, expensive and difficult to secure in position.

One of the objects of the present invention is the pro-

2

vision of means for overcoming the above objections, and the provision of means to which the panels may be secured by nails in such a manner that the nails will be more secure when driven into said means than when driven into wood.

Other objects and advantages will appear in the description and in the drawings.

In the drawings,

Fig. 1 shows the present invention in use supporting panels to provide a suspended ceiling.

Fig. 2 is an enlarged sectional view along line 2—2 of Fig. 1.

Fig. 3 is a perspective view, partly in section, showing special structure for suspending the plasterboard or panels for forming a ceiling.

Fig. 4 is an enlarged fragmentary perspective view, partly in section, showing the method of securing the panel support to the improved hanger of Fig. 3.

Fig. 5 is a fragmentary sectional view showing the manner of securing the hanger to the nailing strip to which the ceiling panels are secured.

Fig. 6 is a fragmentary side elevational view of several side wall panels secured to the device of this invention, with the latter secured to a masonry wall.

Fig. 7 is a sectional view along line 7—7 of Fig. 6.

Fig. 8 is a fragmentary elevational view in which the devices of the present invention are secured by mastic to masonry walls, and in which the wall panels are secured to said devices.

Figs. 1 and 2 are illustrative of a form of the invention in which panels 1 are ceiling panels which are suspended below ceiling joists 2. Hangers 3 of wire may be secured to the ceiling joists and these hangers carry the angle strips 4 or the like.

Secured to these angle strips in crossing relation thereto are the nailing strips of the present invention. Clips, wire, or any other suitable means 6 secure the strips 5.

Fig. 4 clearly shows the construction of each nailing strip, the latter being in the form of a channel having an open upper side, a bottom wall 7, and opposed side walls, the latter being generally designated 8. Each side wall 8 is a double layer of the material of said strip, there being an inner layer 9 and an outer layer 10.

Side walls 8 progressively curve outwardly in direction 45 away from each other in cross sectional contour, commencing from a point spaced from the junctures between the inner layers 9 and the bottom wall 7.

This results in providing substantially planar flanges 11 along the free edges of the side walls. The inner and outer layers 9, 10 are integrally joined along said free edges, with the latter being curved in cross sectional contour.

The outer layers 10 of side walls 8 terminate in free edges 12 adjacent to the bottom wall 7, and the marginal portions 13 along said free edges 12 are preferably inclined or curved in direction away from the edges of the bottom wall that are adjacent thereto.

Between layers 9, 10 of the channel strip 5 is a filler 14. This filler may be of fibrous, moisture resistant material. A strip of 60 lb. asphalt or tar paper has been found to be suitable, and the use of such a strip between the inner and outer layers 9, 10 of each of the side walls 8, not only serves to uniformly space the layers apart, but provides a waterproof body having an adhesive character.

into which the nails 16 (Fig. 7) may be driven. This filler is firmly held between the layers 9, 10 by reason of the curvature forming the flanges 11, and the filler preferably extends into said flanges. The channel strip itself may be of say 26 gauge galvanized iron, which has been found to be suitable.

The space between the marginal portions 13 and the inner layers 9 at the bottom wall 7 provides a recess 15 extending longitudinally of the channel strip into which nails may be driven into the filler 14.

The flanges 11 are preferably apertured equal distances apart, as at 18, for the wire 6 that secures the flanges against the angle strips 4, or nails may be driven through said apertures into wood or masonry.

In operation, after the nailing strips 5 are secured to the angle strips 4, the panels 1 are nailed to said strips, said nails extending through the panels and into recesses 15 and the filler 14.

The nailing strips may be arranged so that a strip will be positioned along each of two opposite edges of the panels, with the marginal portions along each such edge extending approximately halfway across the width of the bottom wall 7 of each strip. Obviously any desired number of nailing strips may be positioned between the two that are at the two opposite edges of each panel. By this arrangement, one nailing strip will be common to the adjacent marginal portions of a pair of adjacent panels.

When nails 16 are driven into the filler 14, the nails will bend to conform to the curvature of the side walls and will thus be held against withdrawal independently of the frictional resistance between the nails and the filler. By using the filler as a spacer between the layers 9, 10, it has been found that the nails driven into the filler will each have substantially the same holding power, a result that would not occur were the layers 9, 10 not spaced apart.

In Figs. 3, 4, 5, a special hanger 20 is used instead of the wires 3 of Fig. 1, and in this instance the bottom wall 7 of each nailing strip is provided with spaced slots 21 extending longitudinally of said bottom wall. The material 22 that is struck from the bottom wall to form each slot may be unsevered from the bottom wall and disposed within the channel of each strip at one end of each slot.

Each hanger 20 may be a metal strap adapted to be nailed or otherwise suitably secured at one end to the ceiling joists 23, and the lower end of each strap has a laterally opening notch 24 in one edge.

These hangers may be secured to the joists as seen in Fig. 3, and their lower ends are then inserted into the slots 21 with the bottom wall 7 at one end of each slot disposed in each notch 24. The material 22 is then knocked down against the edge of the strap that is opposite to each notch and the nailing strip will be secured to the hangers against withdrawal of the latter from the slots.

The panels 1 will then be nailed to the nailing strips the same as has been described for the form of invention described in Fig. 1. It should be noted that the adjacent edges of adjacent panels may be recessed for the slightly protruding end 30 (Fig. 5) of each hanger, or a slight space may be left, which will readily be filled with plaster. These hangers are preferably used only along the adjacent edges of adjacent panels.

Figs. 6, 7 show a nailing strip 5 of the type already described, secured by nails 26 to a masonry wall 25. The space between the panels and such wall may be left open to provide for air insulation or insulating material 27.

In Fig. 8, mastic 28 is the medium that is used for securing the flanges to the masonry wall. In this instance, if desired, slots 29 may be formed in the flanges 11 into which the mastic may be forced if more than normal securing is needed, although this is not ordinarily necessary.

By the structure shown and described, the panels may be nailed to each strip along one or two lines, since there are two open recesses 15 in each strip for nails. The nail-

ing strips are rigid, and the nails will be securely held to the strips. The recesses at their outwardly opening sides are wide enough to permit slight variations in the positions of the nails without affecting the holding characteristics of the nailing strip.

I claim:

1. A nailing strip comprising: a channel strip having opposed side walls, a bottom wall integrally connected along two of its opposite edges with one of the corresponding edges of said side walls, said channel strip having a fully open side opposite to said bottom wall, extensions on said side walls integral therewith along their edges remote from said bottom wall extending over the oppositely outwardly facing sides of said side walls and terminating in free edges extending along and spaced from the junctures between said side walls and said bottom wall, said side walls and said extensions at opposite sides of said channel strip being curved oppositely outwardly along said open side remote from said bottom wall providing coplanar flanges at the juncture of said side walls and said extensions projecting away from each other adapted to be positioned flat against building structure adapted to be connected thereto, said side walls and said extensions being apart for receiving nails therebetween along said opposite edges of said bottom wall.

2. A device for use in securing wall panels, such as plasterboard and the like, to the walls of a room in spaced opposed relation thereto, comprising: a channel strip having a pair of opposed side walls, a flat bottom wall integrally connected along two of its opposite edges with one of the corresponding edges of said pair of side walls, and having an open side opposite to said bottom wall; said side walls having extensions respectively integrally connected therewith along each of said corresponding edges, said extensions being in spaced opposed relation to the oppositely outwardly facing surfaces of said side walls and terminating in free edges that are substantially coplanar with said bottom wall and adjacent to said opposite edges of said bottom wall, said pair of side walls including the said extensions respectively integrally connected therewith being bent oppositely outwardly along the junctures between said side walls and said extensions to provide substantially coplanar flanges, said flanges being formed with openings for connectors adapted to hold said flanges against a surface adapted to be engaged by said flanges, the side of said bottom wall opposite to said open side of said channel being adapted for engaging a side of plasterboard and the like in a position extending across said free edges of said extensions and said extensions being spaced from said side walls for receiving nails extending through such plasterboard into the space between each extension and the side wall adjacent thereto.

3. A device for use in securing wall panels, such as plasterboard and the like, to the walls of a room in spaced opposed relation thereto, comprising: a channel strip having a pair of opposed side walls, a flat bottom wall integrally connected along two of its opposite edges with one of the corresponding edges of said pair of side walls, and having an open side opposite to said bottom wall; said side walls having extensions respectively integrally connected therewith along each of said corresponding edges, said extensions being in spaced opposed relation to the oppositely outwardly facing surfaces of said side walls and terminating in free edges that are substantially coplanar with said bottom wall and adjacent to said opposite edges of said bottom wall, said pair of side walls including the said extensions respectively integrally connected therewith being bent oppositely outwardly along the junctures between said side walls and said extensions to provide substantially coplanar flanges, said flanges being formed with openings for connectors adapted to hold said flanges against a surface adapted to be engaged by said flanges, the side of said bottom wall opposite to said open side of said channel being adapted for engaging a side of plasterboard and the like in a position extending across

said free edges of said extensions and said extensions being spaced from said side walls for receiving nails extending through such plasterboard into the space between each extension and the side wall adjacent thereto, said extensions each being substantially parallel with the side wall adjacent thereto from the terminating ends of said flanges where they are integrally united to the marginal portion of each extension along said free edge thereof, and said marginal portion of each extension along its said free edge being curved away from the side wall adjacent thereto to facilitate the entry of nails into the space between each extension and each side wall.
